UNITED STATES PATENT OFFICE.

RISAKU NISHIMOTO, OF TACOMA, WASHINGTON.

VACUUM-CLEANER.

1,385,573.

Specification of Letters Patent. Patented July 26, 1921.

Application filed March 14, 1921. Serial No. 451,978.

To all whom it may concern:

Be it known that I, RISAKU NISHIMOTO, a subject of the Emperor of Japan, residing at Tacoma, in the county of Pierce and 5 State of Washington, have invented a certain new and useful Improvement in Vacuum-Cleaners, of which the following is a specification.

My invention relates to improvements in 10 vacuum cleaners of the class used for cleaning floors, rugs, carpets and the like and the object of my improvement is to provide a novel and efficient device of this nature that is mechanically operated, the power to drive 15 a vacuum fan that forms a part of the device being derived from the turning of the wheels of the cleaner and being transmitted to the fan through suitable gearing that greatly increases the speed of rotation, the 20 said gearing being constructed so that the fan will always be driven in the same direction by power applied through the wheels regardless of whether the cleaner is moved forward or backward.

25 A further object is to provide a vacuum cleaner having a sweeper brush arranged just in front of the suction nozzle to sweep a rug or carpet and loosen up the dirt and dust so that it will be more easily picked up 30 by the suction of the cleaner.

A further object is to provide a vacuum cleaner of this nature that is strong and simple in construction, reliable and efficient in operation, not liable to get out of order 35 and that is made up largely of standard parts that may be quickly and easily replaced if they become worn.

With the above and other objects in view as will be apparent from the following description the invention consists in the novel 40 construction, adaptation and combination of parts as will be more clearly hereinafter described and claimed.

In the accompanying drawings, Figure 1 45 is a view in side elevation of a vacuum cleaner constructed in accordance with my invention. Fig. 2 is a plan view of the same. Fig. 3 is an inverted fragmentary view showing a portion of the bottom of 50 the vacuum cleaner including the suction nozzle, sweeping brush and mechanism for rotating such sweeping brush. Fig. 4 is an enlarged view in cross section substantially on a broken line 4, 4 of Fig. 2 and Fig. 5 55 is a plan view of the gear mechanism and

driving wheels, parts of the gear housing being shown in cross section.

Like reference numerals designate like parts throughout the several views.

Referring to the drawings, the numeral 6 60 designates a fan housing that terminates at its rear end in an outlet opening 7 with which a dirt or dust collector bag 8 of the usual form may be connected.

Extending horizontally through the fan 65 housing 6 and journaled in the walls thereof is a shaft 10 upon which is secured a fan 11.

12 is a suction inlet passageway that communicates at its upper end with the central 70 portion of the fan housing 6 and that flares outwardly toward its lower end and terminates in a relatively long slot or suction nozzle 13 that is arranged crosswise of the bottom of the cleaner.

75 From the above description it is obvious that when the fan 11 is rotated in the direction indicated by the arrow A air will be drawn upwardly through the nozzle 13 and will be forced outwardly through the outlet 80 7 into the dust bag 8.

Disposed just in front of the nozzle 13 and preferably integral with the housing 6 is a transversely arranged brush housing 14 wherein is mounted a rotary brush 15 of 85 the type common to carpet sweepers. The ends of the brush 15 are secured to bearing studs or shafts 16 upon which are fixedly mounted pinions 17 that mesh with other pinions 18 on short shafts 20 that are secured to relatively small wheels 21 upon which the forward end of the vacuum cleaner is carried, see Fig. 3, so that when the vacuum cleaner is moved and the wheels 21 are rotated the brush 15 will be rotated in 90 the opposite direction from the wheels. The pinions 17 and 18 are preferably disposed within separate compartments 22 provided at the ends of the brush housing.

95 If desired, the brush housing 14 may be made larger and dust receptacles or boxes of the type commonly used in carpet sweepers may be placed therein to catch the dirt that is picked up by the brush 15.

The fan shaft 10 projects rearwardly 105 through the inclined rear wall of the fan housing 6 and is provided with a fixedly mounted bevel gear 23 that meshes with another bevel gear 24 on a transverse shaft 25. The shaft 25 is provided with a pinion 26 110

that meshes with a gear wheel 27 on a shaft 28 which, in turn, has a pinion 30 that meshes with a gear wheel 31 on a shaft 32.

The shaft 32 is provided at one end with 5 a pinion 33 that meshes with a large gear wheel 34 and at the other end with another pinion 35 that meshes with an idler gear 36, which, in turn, meshes with a gear wheel 37.

The gear wheels 34 and 37 are both loosely 10 mounted on a transverse axle shaft 38. The gear wheel 34 is disposed adjacent to a ratchet wheel 40 that is secured to the shaft 38 and that is arranged to be engaged by a click or pawl 41 on the gear wheel 34 in such 15 a manner that when the shaft 38 is rotated in the direction indicated by the arrow B by moving the vacuum cleaner forward the gear wheel 34 will be rotated and will act through the intermediate gears to rotate the fan shaft 20 10. The gear wheel 37 is disposed adjacent to a ratchet wheel 42 that is secured to the axle 38 and that is engaged by a pawl 43 on the gear wheel 37 in such a manner that when the axle 38 is rotated in the direction indicated by the arrow C by rearward movement of the vacuum cleaner the gear wheel 37 will be rotated, and by reason of the intermediate gearing will rotate the fan shaft 10 in the same direction that such shaft was 30 rotated by the gear wheel 34 when the axle 38 was turned in an opposite direction.

Loosely mounted on the ends of the axle 38 are main driving wheels 44 and 45 that are disposed adjacent to ratchet wheels 46 35 and 47 respectively that are secured to the axle 38 and that are engaged by pawls 48 and 50 on the wheels 44 and 45 respectively in such a manner that when the wheel 44 is rotated in the direction indicated by the arrow D by forward movement of the cleaner the shaft 38 will be rotated therewith and when the wheel 45 is rotated in the direction indicated by the arrow E by rearward movement of the cleaner the shaft 38 will be 40 45 rotated therewith.

By the train of mechanism above described it will be understood that when the vacuum cleaner is moved in a forward direction the fan shaft 10 will be rotated in 50 the direction indicated by the arrow A through the medium of the large gear wheel 34 and that when the cleaner is moved rearwardly the fan shaft 10 will be rotated in the same direction by the gear wheel 37, the 55 reversal of motion accomplished by the idler gear 36 offsetting the reversal in direction of the motion of axle 38.

The gear mechanism is preferably 60 inclosed within a housing 51 and the several shafts 25, 28 and 32 are journaled within suitable brackets or supports 52 that are secured either to the gear housing 51 or to the fan housing 6. The axle 38 may be journaled in the gear housing 51. The several

pawls are held in engagement with their respective ratchet wheels by springs 53.

The wheels 44 and 45 are preferably 70 provided with tires of rubber or other soft material having a relatively high coefficient of friction.

The vacuum cleaner is provided with a handle 54 of any desired form by which it may be moved.

The gear train included in this apparatus 75 insures that the fan 11 will be rotated at a high rate of speed thereby producing a strong suction even though the vacuum cleaner is moved slowly across the floor.

This vacuum cleaner is strong and simple 80 in construction, efficient in operation and not expensive to manufacture. It is adapted for any use that an ordinary vacuum sweeper may be put to and is especially well suited for use in locations where the absence of electric current makes the use of electrical 85 apparatus impossible.

From the foregoing description taken in connection with the accompanying drawings 90 the form of construction and method of operation of this vacuum cleaner will be readily apparent, but, while I have described the principle of operation of the invention together with the device which I now consider to be the best embodiment thereof it will be understood that the device shown is merely 95 illustrative and that such changes may be made as are within the scope of the following claim:

A vacuum cleaner of the class described 100 comprising a fan housing having a discharge opening and having an inlet opening that communicates with a relatively long nozzle slot, a fan mounted for rotation in said fan housing, a shaft connected with said fan and projecting rearwardly from said housing, an axle, a wheel loosely mounted on each 105 end of said axle, ratchet means interposed between each of said wheels and said axle and arranged so that one of said wheels will drive said axle in one direction and the other wheel will drive said axle in an opposite direction, two gearwheels loosely mounted on said axle, ratchet means for locking one of said gearwheels against rotation in one direction on said axle and the other gearwheel 110 against rotation in the opposite direction on said axle, a short shaft arranged parallel with said axle, two pinions on said short shaft, one of said pinions meshing directly with one of said gearwheels, an idler gear 115 interposed between the other pinion and the other gearwheel, and speed acceleration gears interposed between and operatively connecting said short shaft and said fan shaft.

In witness whereof, I hereunto subscribe my name this 1st day of March A. D. 1921.

RISAKU NISHIMOTO.
